TELEPHONE-EXCHANGE SYSTEM.

1,139,906.

Specification of Letters Patent. Patented May 18, 1915.

Application filed August 17, 1914. Serial No. 857,131.

To all whom it may concern:

Be it known that I, LIPA POLINKOWSKY, a subject of the Russian Emperor, residing at 19 Rue Brialmont, Brussels, Belgium, have invented certain new and useful Improvements in Telephone-Exchange Systems, of which the following is a full, clear, concise, and exact description.

This invention relates to telephone exchange systems, and more particularly to systems in which a group of calling or incoming lines are served by and connectible to by a group of line finder switches automatically operating when a call exists upon one of such lines to search for and seize such line.

A particular feature of the invention involves means whereby a signal or indication will be given when and only when an insufficient number of line finders accessible to a group of lines are available to hunt for and seize a line upon the initiation of a call upon one of such lines.

A further feature provides simple and positively operating means whereby the number of occasions that the condition above referred to arises may be recorded for any given period of time, so that a positive record may be kept which will indicate whether the number of line finders serving the group of lines is sufficiently large to maintain the usual traffic requirements of the exchange.

In some cases it will be sufficient if a single line finder switch is always available when a call is initiated upon one of the lines to which such line finder switch has access. In this case no indication is necessary, and no record need be made unless when the call is initiated, no line finder switch is available. Under other circumstances it will be necessary for the traffic requirements of the exchange or for other reasons, that a definite number, more than one, of line finder switches should be available to hunt for and seize the calling line immediately that the call is initiated thereon.

The invention will be first described where the requirement is that only one line finder switch need be available when the call is initiated on the calling line. The drawings show so much of the calling line and the apparatus associated therewith, and so much of a line finder switch, and the apparatus associated therewith, as is necessary to illus-

trate the invention. The calling or incoming line is represented by the conductors thereof, 11 and 12. Upon the initiation of a call upon such line, the circuit for direct current will be closed between such conductors, as for example, at the substation thereon by the subscriber removing his receiver from its switchhook, and current will pass through the line relay 13 of the line and over the back contacts of the armatures of the cutoff relay 14 of such line to energize the relay 13 in the usual manner. The energization of the relay 13 closes the circuit for the pilot relays 15, 16, which circuit also places selectable potential upon the terminal 17 of the line in the well understood manner. If at this time a line finder of the group having access to this line is idle, a circuit will be closed over the front contacts of the relays 15, 16, through guard relay 18, to the common point 19, from which point the circuit will be continued through the sequence switch contact 20 and power magnet 21 of all of such idle line finders. These line finders will thereupon begin to move, testing by their test brushes 22 the terminals 17 of all of the lines to which they have access. The first one of the line finders whose brush 22 coming into contact with the terminal 17 and finding the selectable potential thereon, will have the relay 23 thereof energized over its left-hand high resistance winding and the sequence switch contact 24, the path to earth for such circuit being through the interrupter brush 25 and the winding of relay 26. Relay 26, however, does not become energized upon the closure of this circuit, its winding being shunted through the interrupter brush 25. The line finder continues to move until its brushes, including the brush 22, are centered upon the terminals of the calling line when, the circuit through its interrupter brush 25 being opened, the shunt around the power control relay 26 is removed, and such relay will respond, opening the circuit for the power magnet 21 and closing the circuit to the holding magnet 27 of the line finder switch, stopping such switch with its brushes accurately in position upon the terminals of the calling line. As soon however as the relay 23 was energized when the brush 22 came in contact with the terminal 17 upon which existed selectable potential, it closed, through its

armature, the parallel circuit through its low resistance right-hand winding in shunt of its high resistance left-hand winding. This low resistance circuit so reduces the potential upon the terminal 17 that any other line finder switch whose brush 22 comes in contact with the terminal 17 of the same line finds insufficient potential upon such terminal to energize the relay 23 over its left-hand high resistance winding. No other line finder switch, therefore, will be able to seize this calling line.

Coincident with the stopping of the line finder switch by the energization of the relay 15, such relay closes a circuit for the sequence switch 28 over the sequence switch contact 29, to drive such sequence switch out of its first position to come to rest in its third position. In the second position of the sequence switch a circuit is closed over sequence switch contact 30, the line finder brush 31, and terminal 32 individual to the calling line, to energize the cutoff relay 14 of such line. This relay by energizing opens the circuit of the line relay 13 which in turn by de-energizing, opens the circuits of the pilot relays 15 and 16, which in turn will de-energize unless some other line of the same group of lines is calling, and has not as yet been seized by a line finder switch. It will be observed that the conductors connected to the armatures of the line relay 13 of the various lines are connected to the circuit of the pilot relays 15, 16 at the common point 33. If upon the energization of the line relay 13 upon the initiation of a call and the consequent energization of the pilot relays 15 and 16 no line finder switches having access to this line were idle, that is, no line finder switches stand with their sequence switches 28 in the normal or first position, no circuit for the guard relay 18 is closed. The armature of the relay 18 therefore remaining in its retracted position, a circuit is closed for the guard lamp 34 which will indicate to the attendant at the station in which the group of lines referred to terminate, that a call has been initiated on one of such lines, and no line finder is available to extend the circuit of such line. Furthermore, immediately that a line finder of the group having access to such line becomes idle, that is, its sequence switch reaches its first or normal position, the circuit will be closed at its power magnet 21 for relay 18 to energize such relay, and the guard lamp 34 will be extinguished. The attendant will thereby be informed that, unless the calling party has abandoned the call, a line finder is at that time searching for the line on which such call exists. In association with the guard lamp 34 there is also provided a meter 35 the magnet of which will be energized whenever the guard lamp 34 is lighted, and will cause the meter to register, once,

whenever such magnet is deenergized coincident with the extinguishment of the guard lamp 34 either upon a line finder becoming idle to search for the calling line, or upon the abandonment of the call by the calling subscriber. It will be obvious therefore that this meter will indicate the total number of delayed or abandoned calls in the group for any given period, which delayed or abandoned calls are traceable to the insufficient number of line finders associated with the group of incoming lines to which such meter is individual. It will be further observed that if when there are no line finders available to search for lines upon which calls are initiated at any given time two or more lines should be calling in the group, the guard lamp 34 will be lighted, and the meter prepared for registering immediately. When a line finder becomes available to search for the calling lines, the lamp will be extinguished and the meter will register. When however the line finder has found and seized one of the calling lines, the circuit for the relay 18 will be opened at its sequence switch contact 20, and if unseized calling lines still exist in the group, and no line finder has meanwhile become available to search for and seize such lines, the guard lamp will again be lighted and the register 35 again prepared for registration. It will therefore be apparent that the guard lamp 34 will provide an efficient indication of the occasions when no line finder switch is available to extend the circuit of a calling line, and the register 35 will provide an accurate record of the number of such occasions.

In systems in which the traffic or other requirements make it imperative that more than one line finder switch should always be available to search for and seize a line upon which a call is initiated, in order that the extension of the calling line should be accomplished by a line finder switch with the least possible delay, it is only necessary that the guard relay 18 should be so adjusted that it will only respond when, upon the initiation of a call, the minimum required number of line finder switches are in idle position. That is to say, when the minimum required number of available line finder switches is two, the guard relay 18 will be so adjusted that it will only attract its armature when it is energized over a circuit including the power magnets 21 of two of such line finder switches in parallel. The guard lamp 34 will therefore indicate and the register 35 record all occasions on which the initiation of a call upon a line of the group occurs, when there are not two line finder switches at least available to extend the circuit of such line. It is obvious of course that the minimum required number of line finder switches available to extend the connection may be 3, 4, or any other

number, the guard relay 18 being adjusted to be energized only over the power magnets 21 of respectively 3, 4, or any other given number of line finder switches.

5 The invention herein is obviously adaptable either for systems in which the incoming calling lines terminate in main central offices, such lines being either subscribers' lines, or incoming trunk lines, and in which 10 offices there is, or may be, always present an attendant, or to satellite offices where an attendant need not be present, the register maintaining a complete and accurate record which may be observed whenever the attendant 15 visits the satellite office, and indicates definitely whether the number of line finder switches serving the group to which the register is individual is sufficient to fulfil the traffic or other requirements of the exchange.

20 In the drawings, the apparatus and circuits individual to an incoming line, the apparatus and circuits individual to a line finder switch and the apparatus and circuits common to the group of lines and group of 25 line finder switches are shown separated by dotted lines, so that the relation of the various elements of the system in which the invention is shown embodied may be made most clear.

30 I claim:-

1. In a telephone exchange system, the combination with a plurality of lines, a plurality of finder switches in which said lines terminate, means for causing one of said 35 switches to connect with a calling line upon the initiation of a call upon such line, indicating means, and means actuated in initiating a call upon any of said lines to operate said indicating means each time there is not 40 available a definite number of such switches to connect with such calling line.

2. In a telephone exchange system, the combination with a group of lines, finder switches for said group, means for causing 45 one of said switches to connect with a calling line of the group of lines upon the initiation of a call upon such line, indicating means for said group of lines, and means actuated in initiating a call upon any of said 50 lines to operate the indicating means each time there is not available a definite number of switches to connect with such calling line.

3. In a telephone exchange system, the combination with a plurality of lines, finder 55 switches to which such lines are multiplied, means for starting the switches in motion upon the initiation of a call in any of the lines, and indicating means individual to said lines and operated each time there is

not available a definite number of switches to connect with a calling line.

4. In a telephone exchange system, the combination with a plurality of lines, a plurality of finder switches in which said lines terminate, means for causing one of said switches to connect with a calling line upon the initiation of a call by such line, a registering device, a signal, and means for operating said signal and registering device each time there is not available a definite number of such switches to connect with a calling line.

5. In a telephone exchange system, the combination with a plurality of lines, finder switches in which said lines terminate, means for causing one of said switches to connect with a calling line upon the initiation of a call upon such line, indicating means and a pilot relay for said lines, said pilot relay being energized upon the initiation of a call upon any line and closing at one point the circuit of said indicating means, a contact closed when any of said switches is idle, and a relay controlled by said contact to open at another point the circuit of said indicating means.

6. In a telephone exchange system, the combination with a plurality of lines, finder switches for said lines, driving circuits therefor, a pilot relay adapted to close the driving circuits of any of said switches which are in normal position upon the initiation of a call, indicating means for said lines, said pilot relay also closing at one point the circuit of said indicating means, and a relay in the conductor common to the driving circuits of the switches operated if the driving circuit of any switch is closed upon the energization of the pilot relay to open at another point the circuit of said indicating means.

7. In a telephone exchange system, the combination with a plurality of lines, a plurality of automatic switches adapted to serve said lines, means for causing one of said switches to be associated with a calling line, indicating means adapted to be actuated upon the initiation of a call upon any of said lines, and a relay adapted to prevent the actuation of said indicating means if any of said switches is idle.

In witness whereof, I hereunto subscribe my name this 28th day of July A. D., 1914.

LIPA POLINKOWSKY.
